United States Patent Office.

MAX MILLER, OF BROOKLYN, NEW YORK.

Letters Patent No. 60,772, dated January 1, 1867.

TOY WIND-WHEELS.

The Schedule referred to in these Letters Patent and making part of the same.

TO ALL WHOM IT MAY CONCERN:

Be it known that I, MAX MILLER, of Brooklyn, Kings county, State of New York, have invented a new and useful improvement in Toy Wind-Wheels; and I do hereby declare that the following is a full, clear, and exact description thereof, which will enable others skilled in the art to make and use the same, reference being had to the accompanying drawing, forming a part of this specification, in which—

Figure 1 is a vertical longitudinal section of my improved toy wind-wheel.

Figure 2 is a top view of a revolving scroll-wheel.

Figure 3 is an edge view of a revolving screw-wheel.

Figure 4 is a top view of the wheel represented in fig. 3.

Similar letters of reference indicate like parts.

My invention has for its object to furnish a simple, cheap, and amusing toy for children. And it consists of the combination of the mouth-piece, tube air-chamber, pivoting post, and revolving scroll-wheel, or equivalent, with each other, as hereinafter more fully described.

A is the mouth-piece, which is simply an enlargement formed upon or attached to the end of the air-tube, B, and covered with a perforated cap, as shown in fig. 1; or it may have any other convenient form, for effecting the same purpose, which is to receive the air from the mouth and introduce it into the air-tube. B is the air-tube, one end of which is connected to the mouth-piece A, as before described, and the other end is connected with the air-chamber, C, as shown in fig. 1. The air-chamber C may be cylindrical in form, or it may have any other convenient form, and acts as a reservoir to receive the air from the tube B, and discharge it against the revolving-wheel in such a direction as to cause it to revolve and keep it revolving. For this purpose the upper head or side of said air-chamber has a number of small holes formed around its central point, through which the air escapes against the under side of the wheel, causing it to revolve. D is a small vertical post or rod, the lower end of which is securely attached to the centre of the head or upper side of the air-chamber C, and the upper end of which is rounded off to form a pivot upon which the wheel revolves. The revolving-wheels may be made of various forms to give variety to the toy. They may be made in the form of a scroll, E, as shown in figs. 1 and 2, or in the form of a wheel, F, as shown in figs. 3 and 4, or in any other well-known form. But in all cases they should have a depression or socket formed at their centres of gravity, so that they may be balanced and revolve upon the point or upper end of the post D, as shown in figs. 1 and 3. And they should be so formed that the streams of air coming through the holes in the upper side of the air-chamber C, and striking against the under side of said wheels, may cause them to revolve rapidly. If desired a handle may be attached to the lower side of the toy, or the tube B may serve as a handle.

I claim as new, and desire to secure by Letters Patent—

An improved toy wind-wheel, formed by the combination of the mouth-piece A, air-tube B, air-chamber C, pivoting post D, and revolving-wheel E, or equivalent, with each other, substantially as herein described, as a new article of manufacture.

MAX MILLER.
